UNITED STATES PATENT OFFICE.

BRUNO ZINKE, OF SAARBRÜCKEN, GERMANY.

METHOD OF OPERATING FOUR-CYCLE EXPLOSIVE-ENGINES.

1,147,474.

Specification of Letters Patent. Patented July 20, 1915.

Application filed January 21, 1907. Serial No. 353,375.

To all whom it may concern:

Be it known that I, BRUNO ZINKE, a subject of the King of Prussia, residing at Saarbrücken, in Germany, have invented certain new and useful Improvements in or Relating to Methods of Operating Four-Cycle Explosive-Machines, of which the following is a specification.

The methods of working gas engines are well known in which compressed air is used either for the formation of the mixture or for the scavenging of the residues of combustion from the cylinder, but in spite of the fact that persons highly skilled in the art agree as regards the value of the scavenging, the scavenging has not been successfully accomplished because of the too great difficulties encountered in carrying it into practice. The attempt therefore to obtain special scavenging has been abandoned. It has been proposed to attain this object by providing the cylinder of a four-cycle gas engine with three chambers, two of which communicate with a supply of air under pressure while the third may be filled with compressed gas. These chambers are cut off from the supply pipes at stated intervals and their contents allowed to expand into the cylinder through regulated valves, the expansion of air from one of the chambers causing the flushing after which the compressed mixture is admitted into the cylinder. This method of working, however, is open to objection in that the machine is complicated by the provision of the various valves and a separate air chamber for flushing the cylinder. Moreover, owing to the cutting off of the supply of gas and air to the chambers during the opening of the cylinder inlet valves, the charging of the cylinder does not take place under pressure which remains equal, but drops because of the expansion of the gas and air from the closed chambers.

The present invention gives a practical method for expelling the residual products of combustion from gas engines of the four cycle type this being effected by air which enters the cylinder through the main inlet valve under approximately permanent pressure.

To obtain diagrams always uniform the first condition is, as is well known, that the gas and air should be as far as possible under the same pressure, and that the said

pressures should practically remain the same relatively to each other. For this reason, the air in the air pipe is placed, according to the present invention, permanently under pressure by means of a separate air pump driven in any convenient manner. This pressure corresponds to that in the gas-pipe, and amounts to about 100 centimeters water column above atmospheric pressure.

A constructional form of a four-stroke engine for executing the method according to this invention is represented in the accompanying drawing.

Figure 1 is a cross-section through the cylinder showing the gas and air admission devices; Fig. 2 a longitudinal section through the gas and the main inlet-valve; and, Fig. 3 a working diagram.

The gas is under pressure in a gas receptacle *a* provided underneath the engine and proceeds to the cylinder *c* through a tube *b*. By means of a regulated valve *d* controlled by the regulator, the gas is admitted into the mixing space *e* and from this by means of a regulated valve *f* into the cylinder, together with air. The air proceeds by means of a blower *g* driven by the engine, through a conduit *h* into the mixing space *e* and is kept continuously under pressure. The combustion gases are discharged by means of a regulated valve *i* arranged in the lower part of the cylinder *c*.

The engine works in the following manner: The main inlet valve is opened in any known manner during the last part of the exhaust stroke. Air then enters the cylinder from the space *e* and scavenges or sweeps out the remaining residues of combustion through the still-open outlet-valve *i*. On the closing of the outlet valve at the end of the exhaust stroke the gas inlet valve *d* is opened. The gas thereupon enters with the air which is normally under pressure during the suction stroke, into the cylinder. The gas inlet valve *d* is only closed toward the end of this stroke and the inlet valve *f* at the end of the stroke itself. In this manner the presence of any residuary gas in the mixing space is avoided so that on the opening of the inlet valve *d* during the exhaust only pure air enters the cylinder. No loss of gas therefore occurs.

In Fig. 3 the diagram drawn in full lines is the usual diagram of gas engines, and that

shown in dotted lines is one obtained by the new method. The cross-hatched area represents the work gained.

Owing to the better state of the mixture, 5 it is possible with a considerably smaller compression to obtain the same pressure of ignition at the moment of ignition as with a higher compression in the case of a mixture spoiled by products of combustion. 10 The gain of work shown by the diagram is considerably greater than the work used for putting under pressure the whole quantity of air, as, owing to the arrangement of a separate pump, the air is compressed only 15 to the pressure really necessary.

This new process is especially suitable for small loads on the engine, in which case, as is well known the engine runs irregularly, is difficult to connect up in parallel and works 20 with faulty ignitions. This is due to an incorrectly composed and poor mixture, as for small loads the detrimental effect of the residues of combustion is greatest and, furthermore, the oscillations in the conduit for 25 the gas and air are greatest.

Having thus fully described my invention, what I claim and desire to secure by Letters Patent is:—

The method herein described of operating 30 four-cycle scavenging internal combustion

engines consisting in separately supplying gas under pressure to the intake, separately supplying air to the intake under a practically constant predetermined pressure practically equal with the pressure of the gas, 35 separately admitting air only from the said air supply into the cylinder toward the end of the exhaust stroke to sweep out the residues of combustion through the opened outlet valve of the cylinder, closing the outlet valve 40 of the cylinder immediately on the commencement of the charging stroke, admitting thereupon gas from the said gas supply into the cylinder, while the air continues to enter the cylinder with the proper amount of gas 45 mixed therewith during the charging stroke, compressing the gas and air mixture during the compression stroke, expanding the explosion gases during the expansion stroke, and positively expelling the exhaust gases by 50 the piston through the opened valve during the exhaust stroke.

In testimony whereof I have signed my name to this specification in the presence of two subscribing witnesses.

BRUNO ZINKE.
